United States Patent Office

Des. 204,764

Patented May 17, 1966

204,764

MEDAL

Francois Valentin, 13 Ave. Raymond Feraud,
Nice, France

Filed Oct. 30, 1964, Ser. No. 82,410

Term of patent 7 years

(Cl. D29—19)

FIG. 1.

FIG. 2.

FIG. 3.

FIG. 1 is a front view of a medal showing my new design;

FIG. 2 is a side view thereof; and

FIG. 3 is a rear view thereof.

The essential features of the design reside in the portions shown in solid lines.

I claim:

The ornamental design for a medal, as shown and described.
